UNITED STATES PATENT OFFICE

ARTHUR J. TRUELSON, OF SALT LAKE CITY, UTAH

DESIGN FOR A RADIO CABINET PANEL

Application filed October 8, 1928. Serial No. 28,411. Term of patent 7 years.

To all whom it may concern:

Be it known that I, ARTHUR J. TRUELSON, a citizen of the United States, residing at Salt Lake City, in the county of Salt Lake, State of Utah, have invented a new, original, and ornamental Design for Radio Cabinet Panels, of which the following is a specification, reference being had to the accompanying drawing, forming part thereof.

Figure 1 is a front elevation of the radio panel showing my new design.

Figure 2 is a section on line 2—2 of Figure 1.

I claim:

The ornamental design for a radio cabinet panel as shown.

ARTHUR J. TRUELSON,
